(57) **CLAIM**

The ornamental design for a processing machine for bran-free rice, as shown and described.

DESCRIPTION

FIG. 1 is a perspective view of a processing machine for bran-free rice embodying our design;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top plan view of FIG. 1;

FIG. 7 is a bottom plan view of FIG. 1; and,

FIG. 8 is a sectional view taken along line A—A of FIG. 6.
